BREAD TRAY

Houston Rehrig, 100 Los Altos Drive,
Pasadena, Calif. 91105

Filed Oct. 25, 1972, Ser. No. 300,552

Term of patent 14 years

Int. Cl. D3—99

U.S. Cl. D87—1 R

FIG. 1

FIG. 2

FIG. 3

FIG. 4

FIG. 5

FIG. 1 is a perspective view of a bread tray showing my new design;

FIG. 2 is an end elevation view thereof;

FIG. 3 is a side elevation view thereof;

FIG. 4 is a top plan view thereof, and

FIG. 5 is an enlarged bottom plan view showing a quarter portion of the bread tray the other three-quarters being substantially the same in appearance as the portion shown.

I claim:

The ornamental design for a bread tray, substantially as shown and described.
